United States Patent Office.

GEORGE COOPER, OF NEW YORK, N. Y., ASSIGNOR TO VICTOR E. MAUGER,
OF SAME PLACE.

Letters Patent No. 78,930, dated June 16, 1868.

IMPROVEMENT IN LITHOGRAPHIC PRESSES.

The Schedule referred to in these Letters Patent and making part of the same.

TO ALL WHOM IT MAY CONCERN:

Be it known that I, GEORGE COOPER, of the city, county, and State of New York, have invented a new and improved Damping-Apparatus for Lithographic Machines and Presses; and I do hereby declare that the following is a full, clear, and exact description thereof, which will enable others skilled in the art to make and use the same, reference being had to the accompanying drawings, forming part of this specification, in which—

Figure 1 represents a plan or top view of my improved damping-apparatus.

Figure 2 is a longitudinal vertical section of the same, taken on the plane of the line $x'x$, fig. 1.

Figure 3 is a vertical transverse section of the same, taken on the plane of the line $y'y$, fig. 2.

Figure 4 is a detail vertical section, taken on the plane of the line $z'z$, fig. 1.

Similar letters of reference indicate corresponding parts.

This invention relates to a new device for damping the printing-surface and the edges of lithographic stones automatically, so that in machine lithographic printing, the required moisture may be imparted to the stone. Ever since the introduction of machine lithographic printing, the proper equal moistening of the stones has presented the greatest difficulty.

My invention consists, first, in the use of a water-reservoir with a slotted bottom, in which felt, blanket, or other porous fabric is clamped, so as to conduct the water below the reservoir with the requisite slowness. The said fabric or swab can be clamped by suitable mechanism, so that the discharge of water from the reservoir can be regulated at pleasure.

The invention also consists in securing the lithographic stone upon a movable carriage, and in fixing upon the same carriage another stone or slab, which receives the moisture from the aforesaid swab projecting from the water-reservoir, to transfer it to the printing-stone.

The invention also consists in the arrangement and construction of a series of revolving or other porous wipers or rollers, which take the moisture from the surface and edges of the slab and transfer it thence to the surface and edges of the printing-stone.

A, in the drawing, represents a trough, cistern, or suitable water-reservoir, fitted to suitable supports, and having a slotted bottom, as shown in fig. 2. The width of the slot is adjustable by means of set-screws $\alpha\alpha$, or their equivalent, as indicated.

Through the slot in the vessel A is passed a woollen, felted, or other suitable porous and absorbing fabric or material, B, by which the water is slowly carried to the lower extremity of such filling. The said filling B may be made in single, double, or more layers, may terminate below the vessel A in a bag, which is filled with sponge, or other suitable material, or may be otherwise arranged, as may be desired.

C represents a sliding carriage, moving under the vessel A upon suitable rails. Upon the carriage C is secured, near to that end which is furthest from the vessel A, the printing-stone D, and in line with the same, nearer to the vessel A, another stone, E, of similar size as the stone D, as shown. During the reciprocating motion of the carriage the slab E passes under the cloth B, and receives moisture from the same.

F is a horizontal roller, fitted in bearings, hereafter described, and covered with felt, or other suitable absorbing-material. As the slab E passes from under the cloth B, it comes below the roller F, which absorbs the moisture from the slab.

G is a horizontal wiper, covered with sponge, or other suitable material. The roller F and wiper G have their bearings in plates $b'b$, which are drawn down by means of springs c , as in fig. 4, so that the roller F and wiper G may always be drawn upon the surfaces of the stones. The wiper G is drawn so much down that it will come in contact with the front and back edges of the slab, so as to absorb the moisture from the same.

H H are pieces of sponge, or other absorbing-material, which are fitted to the lower ends of adjustable bars or springs $d'd$, and which are to wipe the side edges of the slab.

The joints of the vessel A are kept tight by means of suitable rubber packing, as shown.

The operation is as follows: As the carriage moves in the direction of the arrow 1, fig. 2, the slab E is brought under the cloth, B, and is wetted by the same, the set-screws *a* regulating the quantity of water deposited upon the slab. The carriage is then moved in the direction of arrow 2, fig. 2, and the slab E is still more wetted. An elastic plate, I, is arranged in front of the trough A, so as to sweep over the surface of the slab as the same moves under it. The object of the plate I is to distribute the moisture evenly upon the surface of the slab, and to remove the surplus.

During its continued motion in the direction of the arrow 2, the slab arrives under the wipers H, which take the moisture from its side edges, then under the roller F, which absorbs the moisture from the surface, and finally under and against the wiper G, which absorbs it from the back and front edges.

The motion of the carriage is then again reversed, and the slab passes once more under all the rollers and wipers, which complete their respective services, and then the stone D arrives under the same roller F, and under the wipers G, H H, which give off their moisture to the stone and to its edges.

Thus the stone is automatically damped, the degree of moisture being easily regulated by the set-screws *a a*, or their equivalents, and by the up-and-down adjustable wiper I, the manner of attachment of which is fully shown in fig. 3.

The bars *d*, from which the wipers H are suspended, work up and down adjustably in slotted plates *e*, so that the said wipers H may be adapted to stones of greater or less width and thickness.

Having thus described my invention, what I claim as new, and desire to secure by Letters Patent, is—

1. Wetting a lithographic stone by moistening the surface of another stone, and transferring the moisture from the same to the printing-stone, as described.

2. Wetting a lithographic stone by means of a moist roller or rollers, F, and wipers H H, G, under and between which the stone passes, substantially as described.

3. The water-containing vessel A, when provided with an adjustable slot that is filled with absorbing-material or fabric B, substantially as herein shown and described.

4. The up-and-down adjustable elastic plate I, when arranged as set forth, for the purpose of equally distributing the moisture over the slab E, in the manner specified.

5. Securing the wipers H H to adjustable bars or springs *d d*, for the purpose of adapting the machine to stones of greater or less width and thickness, as specified.

6. The combination of the slotted vessel A, cloth, B, screws, or their equivalents, *a*, carriage C, stones E, wipers F, G, and H, and distributor I, with each other and with the stone, D, all made and operating substantially as and for the purpose herein shown and described.

The above specification of my invention signed by me, this 25th day of November, 1867.

GEORGE COOPER.
